Fig. 3

Fig. 5

FIG. 1 is a plan view of the shackle lock embodying my new design.

FIG. 2 is a front elevation in closed position thereof.

FIG. 3 is a side elevation in closed position thereof.

FIG. 4 is a bottom view thereof.

FIG. 5 is a front elevation in opened position thereof, and the FIGS. 1 to 5 showing a design consisting of a sphere, opposite poles have a central axis through the sphere each having a circular flat face formed on said sphere, said faces being same size and parallel to each other, an equatorial, cylindrical band formed around the sphere equidistant between the said faces, said band having a width that is approximately equal to an axial distance between said band and each said face; a pair of cylindrical projections axially parallel to each other and to said axis, said projections protruding from one generally hemi-spherical surface of said sphere and being located close to diametrically opposite edges of one of said faces, the ends of said projections being aligned

along a same level plane as said face; and a short, spiral-wound cable having opposite ends extending from said projection ends, said cable being enclosed in a transparent sleeve.

I claim:

The ornamental design for a shackle lock, as shown.
